UNITED STATES PATENT OFFICE.

LOUIS CHAPT, OF PATERSON, NEW JERSEY.

ACETYLENE-TORCH.

1,278,303.

Specification of Letters Patent.

Patented Sept. 10, 1918.

Application filed April 17, 1918. Serial No. 229,152.

To all whom it may concern:

Be it known that I, LOUIS CHAPT, a citizen of the Republic of France, residing at Paterson, in the county of Passaic and State of New Jersey, have invented certain new and useful Improvements in Acetylene-Torches, of which the following is a specification.

My invention relates to improvements in torches for cutting, welding, brazing, pre-10 heating, and the like, and adapted to use various forms of gaseous fuel, such as acetylene and oxygen, or ordinary gas and air.

An important object of the invention is to provide a torch of the above mentioned 15 character which is readily convertible, for any of said purposes, of simplified construction, and reliable and safe in operation.

Other objects and advantages of the invention will be apparent during the course 20 of the following description.

In the accompanying drawings forming a part of this specification and in which like numerals are employed to designate like parts throughout the same,

25 Fig. 1 is a central vertical longitudinal sectional view through apparatus embodying my invention.

Fig. 2 is a transverse sectional view taken on line 2—2 of Fig. 1,

30 Fig. 3 is a similar view taken on line 3—3 of Fig. 1,

Fig. 4 is a perspective view of an agitator element,

35 Fig. 5 is a similar view of a coacting agitating element,

Fig. 6 is a longitudinal section through the head of the torch, showing the attachments for welding,

40 Fig. 7 is a longitudinal section through a preheating attachment, and,

Fig. 8 is a similar view through a Bunsen burner attachment.

In the drawings wherein for the purpose of illustration is shown a preferred embodiment of my invention, the numeral 10 designates a bushing, and a second bushing 11 is arranged forwardly of and spaced from the first bushing, these two bushings being held within the ends of a tube 12, by any suitable means.

45 The numeral 13 designates an interior coupling, provided at its rear end with a reduced extension 14, exteriorly screw-threaded, as shown at 15, to engage within the screw-threaded opening of the bushing 10.

The screw-threaded extension 14 projects beyond the bushing 10 and engages within a chamber 16 of a valve casing 17, to be connected with a source of oxygen or air. The valve casing 17 is provided with a chamber 18, separated from the chamber 16 by means of a bridge 19, having an opening 20, covered and uncovered by a needle valve 21, having screw-threaded engagement within a bearing 22.

50 The tubular coupling 13 is provided at its forward end with a reduced extension or nozzle 23, exteriorly screw-threaded and projecting into a tubular mixing chamber 24, and having screw-threaded engagement 70 therein, as shown. At its forward end, the tubular mixing chamber 24 is provided with an enlarged head 25, having a flange 26, contacting with an inner tubular casing 27, which engages within an annular flange 28, 75 formed upon the bushing 10, as shown.

75 The numeral 29 designates a valve, such as a needle valve having connection with a source of acetylene gas, or other gaseous fuel, and connected with an elbow 30, having 80 a reduced screw-threaded portion 31, engaging within an opening formed in the bushing 10, and discharging interiorly of the flange 28 and into the inner tubular casing 27, as shown.

85 Formed upon the tubular coupling 13 is an agitator flange 32, fitting snugly within the inner tubular casing 27, and provided upon its periphery with inclined grooves 33, adapted to impart a rotary movement to the 90 gases passing therethrough. The gas enters a space 34, exteriorly of a tubular wire gauze element 35, as shown.

95 The tubular mixing chamber 24 is provided at its rear end with an agitating flange 36, having inclined or spiral ports 37 formed therein, and discharging into a space 38, exteriorly of a tubular wire gauze element 39. The function of the tubular wire gauze elements 35 and 39 is to prevent back firing of 100 the apparatus, as is obvious. The tubular mixing chamber 24 is provided forwardly of and near the flange 36 with transverse openings 40, whereby the acetylene gas or the like passes into the tubular mixing chamber. 105 The oxygen or the like is supplied into this chamber through the nozzle 23.

110 Connected with the head 25 is a gas pipe 41, extending through an opening 42 in the bushing 11. The pipe 41 has screw-thread-

ed engagement within an opening 43, formed in a head 44, and communicating with a port 45. The head 44 has a main longitudinal bore 46. The numeral 47 designates an oxygen pipe, the rear end of which leads into the chamber 18, and this pipe has a cut-off valve 48 connected therein, to control the volume of oxygen passing therethrough. The pipe 47 leads into the upper end of the head 44 and discharges into the main bore 46 and a bushing 49 is screw-threaded into the upper end of the head 44, and surrounds the end portion of the pipe 47, and engages suitable packing 50, to prevent leakage.

15 The numeral 51 designates a tubular oxygen ejector, provided at its upper end with an enlarged head 52, contacting with a shoulder 53. The head 52 is slightly smaller in diameter than the bore 46 and thereby permits of the passage of the mixture of acetylene gas and oxygen into and through the bore 46, the head 52 forming a gas tight contact with the shoulder 53, whereby the oxygen passes entirely longitudinally through the tubular ejector 51.

20 The numeral 54 designates a tubular tip provided at its upper end with a reduced extension 55, exteriorly screw-threaded to engage within a screw-threaded recess 56. The bore of the tubular extension 55 and the tip 54 has a larger diameter than the tubular ejector 51, to permit of the passage of the acetylene gas discharging through ports 51', as shown. At its lower end, the tubular ejector 51 has a reduced tubular extension 57, extending through a contracted bore 58, in the tip 54, and the extension 57 having a slightly smaller diameter than the bore 58. It is thus apparent that the oxygen will discharge through the tubular extension 57, and while passing from the free end thereof, will be surrounded or enveloped in a tubular jacket of a mixture of oxygen and acetylene gas, emerging from the bore 58. The mixture of oxygen and acetylene gas is ignited at the end of the tip 54, as is obvious, for cutting purposes.

25 In Fig. 6, I have shown an attachment which is particularly well adapted for use in welding, and this attachment embodies a tip 59 having a longitudinal bore 60, and provided at its upper end with a screw-threaded opening 61, receiving a reduced screw-threaded extension 62, of a coupling 55. This coupling 63 is screw-threaded within the screw-threaded bore 55 of the head 44, and is held against accidental rotation by a lock nut 64, as shown. The coupling 63 is provided at its upper end with a closed head 65, the upper end of which is rounded and adapted to be slightly spaced from the shoulder 53, to permit of the passage of the oxygen therebetween. The coupling 63 is provided with a plurality of apertures 67, disposed near the lower end

of the head 65, as shown. The head 65 has a slightly smaller diameter than the diameter of the bore 46, whereby the oxygen and acetylene gas from the tubes 41 and 47 become mixed, and pass through the apertures 67 into the tubular coupling 63, wherein they are further mixed, and discharge into the bore 60. This mixture discharges from the free end of the tip 59 and is ignited, as is obvious.

30 In Fig. 7, I have shown a different form of tip, for use in preheating, the same embodying a tubular guard 68, having a screw-threaded extension 69 to engage within the screw-threaded opening 55, the coupling 63 being of course removed. The tubular extension 69 receives a tip 70, the discharge end 71 of which is arranged within the tubular guard 68. In the use of this form of attachment, the mixed oxygen and acetylene gas pass through the tip 70 and discharge into the tubular guard 68, and are ignited in the tubular guard or at the discharge end thereof.

35 In Fig. 8, is shown an attachment of the Bunsen type embodying a tubular portion 72, provided at its rear end with an extension 73, exteriorly screw-threaded to engage within the screw-threaded bore 55, the other attachments being removed. Within the tubular extension 73 is a tip 74, having a discharge end 75, arranged within the tubular portion 72. Air supply openings 76 lead into the tubular portion 72, at or near the tip 75.

40 In the operation of the first form of apparatus, by the manipulation of the needle valve 29, a proper amount of acetylene gas is supplied into the rear end of the tubular casing 27, and this gas passes through the grooves 33 and into the space 34 exteriorly of the wire gauze 35. The gas then passes through this wire gauze into the inner portion of the space 34 and then through the ports 37 exteriorly of the wire gauze 38. The gas then passes inwardly through the wire gauze 38 and through the apertures 40, into the tubular mixing chamber 24. When in the tubular mixing chamber, the acetylene gas is brought into contact with the oxygen supply therein through the nozzle 23, by the manipulation of the needle valve 21. This gaseous mixture then passes through the pipe 41 and discharges into the bore 46, and passes exteriorly of the oxygen ejector 51, and discharges from the forward end of the tip 54. Oxygen also passes through the pipe 47 and passes through the oxygen ejector 51, to be discharged from the extension 57 thereof, into the tubular mass of gas passing from the tip 54.

45 In view of the statement of the operation of this form of the invention, it is thought to be unnecessary to explain the operation of the other forms.

It is to be understood that the forms of my invention herewith shown and described are to be taken as preferred examples of the same and that various changes in the shape, 5 size, and arrangement of parts may be resorted to without departing from the spirit of the invention or the scope of the subjoined claims.

Having thus described my invention, what 10 I claim is:—

1. Apparatus of the character described, comprising a tubular casing having its opposite ends closed, a tubular coupling arranged within the tubular casing and provided at its forward end with a discharge nozzle and having a radially extending flange to substantially contact with the inner wall of the tubular casing, said flange having inclined openings formed therein, 15 means for supplying oxygen into the tubular coupling, means for supplying acetylene gas into the tubular casing exteriorly of the tubular coupling and rearwardly of the flange, a tubular strainer element arranged 20 within the tubular casing and disposed inwardly of said inclined openings, a tubular mixing chamber receiving the nozzle in one end thereof and provided near its rear end with a radially extending flange to substantially 25 contact with the inner wall of the tubular casing, said last named flange having inclined ports formed therein and the tubular mixing chamber having transverse ports arranged near the nozzle, a tubular 30 strainer element surrounding a portion of the tubular mixing chamber and arranged inwardly of the outlet ends of the inclined ports, a pipe leading into the forward end 35 of the tubular mixing chamber, and a burner 40 connected with the pipe.
2. Apparatus of the character described, comprising a tubular casing, a tubular coupling arranged within the tubular casing and provided at its forward end with a 45 screw-threaded portion, an oxygen supply valve having a plurality of chambers with one chamber receiving the rear end of the tubular coupling, an oxygen pipe leading into the other chamber of the valve, an acetylene gas valve discharging into the 50 tubular casing, a tubular mixing chamber having screw-threaded engagement with the forward screw-threaded portion of the tubular coupling and arranged within the tubu-

lar casing and having transverse ports 55 formed therein, a gas pipe connected with the forward end of the tubular mixing chamber, and a burner connected with the oxygen and gas pipes.

3. In apparatus of the character described, a tubular casing, a tubular element arranged within the tubular casing in substantially concentric spaced relation and having transverse ports formed in the forward portion thereof, gauze means arranged 60 within the tubular casing and surrounding the tubular element, means for supplying acetylene gas into the tubular casing exteriorly of the tubular element whereby the acetylene gas passes through the transverse 65 ports, means coacting with the gauze means to cause said acetylene gas to pass transversely through said gauze means prior to its passage through the transverse ports, means to supply oxygen into the tubular 70 element, a conduit connected with the tubular element, and a burner connected with the conduit.

4. In apparatus of the character described, a head provided with a main longitudinal bore and a longitudinal opening formed through the upper end thereof and leading into the bore, said head being provided at the upper end of the bore with an internal annular flange, said head being provided forwardly of the flange with a transverse port leading into the bore; an oxygen supply pipe leading into the longitudinal opening; a bushing screw-threaded within the longitudinal opening and surrounding 85 the end of the oxygen supply pipe; packing arranged between the bushing and said flange; a tubular oxygen ejector extending into the bore of the head and provided with an enlarged head adapted to contact with 90 the flange, said head having a smaller exterior diameter than the diameter of the bore; a tubular tip surrounding the forward end of the tubular oxygen ejector and having a reduced screw-threaded portion projecting into the said bore, the reduced screw-threaded portion having a bore of larger diameter than the oxygen ejector; and a gas supply pipe leading into the transverse opening.

In testimony whereof I affix my signature.

LOUIS CHAPT.
